UNITED STATES PATENT OFFICE.

ALBIN HAJOS, OF CHATTANOOGA, TENNESSEE.

CRAVAT.

SPECIFICATION forming part of Letters Patent No. 529,732, dated November 27, 1894.

Application filed June 16, 1893. Serial No. 477,795. (No model.)

To all whom it may concern:

Be it known that I, ALBIN HAJOS, a citizen of the United States, residing at Chattanooga, in the county of Hamilton and State of Tennessee, have invented a new and useful Improvement in Cravats, of which the following is a specification.

My invention relates to an improvement in cravats of the kind to be folded by hand, and 10 more particularly to that class in which the cravat is combined, or formed integral with the collar.

My invention consists in the general and specific details of construction and combination of parts, all as hereinafter more fully set forth.

In the drawings — Figure 1 represents a standing collar provided with a cravat integral therewith and having one long and one 20 short end. Fig. 2 is a view of the cravat shown in Fig. 1 detached from a collar. Fig. 3 is a view of the combined collar and cravat shown in Fig. 1 in the first step of folding. Fig. 4 is a view of the combined collar and 25 cravat shown in Fig. 3 in the final step of folding and before locking, as with a button. Fig. 5 is a view similar to Fig. 4, showing the button applied; and Fig. 6 is a vertical, transverse section on the line 7 of Fig. 5.

30 A represents the cravat proper, comprising the strip *t*, which may be enlarged into the form of a standing or turn-down collar, and provided toward each extremity with a perforation *s*. Beyond the perforation *s*, on one 35 side, the strip is slotted as shown at *r*, and from this point the cravat is deflected downward, as shown at *q*. At the opposite end beyond the other perforation *s* the strip *A* is 40 cut to present the double taper *p* and the double taper *o*, at the junction of which double tapers is provided the perforation *n*, while at the end of the double taper *o* is provided the perforation *m* beyond which the material is deflected, as shown at *l*. At about 45 the point of the perforation *m*, the material is cut out on a curved line, as shown at *k*. The center of each double taper is represented in the drawings by a dotted line respectively *p'* and *o'*, this line designating the 50 folding line of each loop.

The operation of folding the cravat made from the strip described, whether forming part of the collar or not, as is shown in Figs. 3 to 5, is effected as follows: The strip *t* is curved and one edge adjacent to one perforation *s* is introduced into the slit *r* in such a manner that the two perforations *s* shall exactly coincide. The remainder of the strip, or that between the perforations *s* and the extremity *l*, is then curved upon itself in a complete circle, to cause the perforation *m* to coincide with the perforations *s*, while the end *l* projects in the opposite direction to the end *q*. The center of the prolongation of the strip is then forced inward, to cause the perforation *n* to coincide with the perforations *m* and *s*, and the shank *h* of the button *B* is introduced into all the perforations, and the head *h'* of the button then applied in the usual manner with detachable buttons. The face of the 70 button *B* is by preference given the appearance of the central fold of a cravat, so that the effect obtained from a cravat made and folded in this manner, with the button *B* applied, is substantially like that obtained with 75 the ordinary made up cravat of the same general character. In practice the base *h* of the button would be at the inner side of the neckband *x* of the shirt and the shank would pass through a perforation or button-hole therein. 80

Where the strip *A* is separate from the collar, I find it desirable to make it in different sizes,—each size adapted to a collar of a certain size;—but where it forms part of the collar this is obviously unnecessary. 85

What I claim as new, and desire to secure by Letters Patent, is—

A cravat, comprising a strip *A* having the plain part *t* and one end formed with the double tapers *o* and *p*, deflected portion *l* and cut-away part *k* and the opposite end with the deflected portion *q* and slit *r*, perforations suitably located therein, in combination with a retaining button adapted to enter the perforations, as and for the purposes set forth. 90

ALBIN HAJOS.

In presence of—

W. N. WILLIAMS,
M. J. FROST.
